Attest,

UNITED STATES PATENT OFFICE.

JULIA LUEDERS, OF ST. LOUIS, MISSOURI.

CHAIR.

SPECIFICATION forming part of Letters Patent No. 358,466, dated March 1, 1887.

Application filed January 25, 1886. Serial No. 189,677. (No model.)

To all whom it may concern:

Be it known that I, JULIA LUEDERS, of the city of St. Louis, in the State of Missouri, have invented certain new and useful Improvements in Chairs, of which the following is a full, clear, and exact description, reference being had to the accompanying drawings, forming part of this specification, and in which—

Figure 1 is a side elevation of my improved chair. Fig. 2 is a similar view with the body lowered and the back and foot-rest inclined. Fig. 3 is a view of the seat and foot-rest removed. Fig. 4 is a front view. Fig. 5 is a top view with both of the arms opened and the pivoted arm swung partly around into position for use as a table. Fig. 6 is a vertical section taken on line 6 6, Fig. 2. Fig. 7 is an enlarged detail vertical section taken on line 7 7, Fig. 2.

My invention relates to a chair intended for use by invalids or for ordinary use as a reclining or parlor chair; and my invention consists in features of novelty hereinafter fully described, and pointed out in the claims.

Referring to the drawings, A represents the body of the chair, connected by vertical posts B to the removable rockers C by spring-pins D. The form of these pins is illustrated in Fig. 7.

A spiral spring, E, fitting within a pocket, F, between a plate, G, is secured to the outside of the rocker and transverse pin H. The action of the spring is to hold the pin D in its inner position, which fits in holes B', made in the posts B. There are preferably four of these posts and a pin for each post, as shown, and by pulling outward on the pin the body of the chair may be raised or lowered to any desired height. It is shown raised in Fig. 1 and lowered onto the rockers in Fig. 2.

I represents the back of the chair, hinged to the body at I', and held to any desired inclination by a ratchet-bar, J, engaging pins J' on and pivoted at J² to the back. By raising upward on the inner free ends of the bars they are released from the pins J and the back allowed to recline more or less. By pushing upward or forward on the back the bar slips over the pins J' and holds the back to any desired inclination.

K represents the head-rest of the back. It is provided with plates K² and pivoted to the

back at K'. The plates K² have perforations K³, in which fit spring-pins K⁴, that pass through the back, as shown. The form of these pins is the same as those, D, shown in Fig. 7, and are operated in the same manner. By pulling out on the pins the head-rest may be adjusted from the position shown in Fig. 1 to that shown in Fig. 2.

L represents the seat of the chair removably supported on the body by a wooden base, L', fitting in mortises L² in the body A. (See Fig. 6.) It is supported by a seat, M, having a hole or opening, M', beneath which is a commode, M², in a box, M³. (See Fig. 6.) Said box is provided with ribs or flanges m, which slide in grooves m' in the strips or projections m² on the under side of seat M, thus enabling its removal. When the seat proper, L, is in place, the seat M and the commode are entirely hid from view.

N represents one of the arm-rests, which is pivoted at N' to the body A, so that it is capable of being swung around in front of the person using the chair to serve as a table. It is made in two parts, hinged together at N². The under part of the one that does not fold is provided with an opening, N³, which may be used for any desired purpose. The free end of the one that swings around has an extension, N⁴, which fits over the body A on the other side of the chair, at N⁵, to support it.

O represents a foot-rest, pivoted at O' to the seat, and provided with a plate, O², having perforations O³, to receive spring-pins O⁴, of the form and operating in the same manner as the pins D, Fig. 7. By the use of these pins the foot-rest may be held in any desired position, as shown in Figs. 1 and 2.

The rockers C rest upon a base, P, that may be provided with casters, if desired, and this base may be provided with hooks Q, which may be engaged with the front pin, D, by pulling the latter out to receive the hooks. The object of this is to prevent the chair from rocking when desired. The hooks are pivoted forward of the pins D, so that should the chair rock forward the pins will not fall down out of engagement, but will remain in the upper position to stop the chair from rocking backward.

The rockers C are provided with plates C², in which fit the posts B, and in which the

posts move vertically. The rockers are also connected with the base by springs as usual.

I claim as my invention—

1. A chair having a base, removable rockers supported on the base, and a vertically-adjustable body secured to the rockers and adjustable independently thereof, substantially as shown and described, for the purpose set forth.
2. A chair having removable rockers and a vertically-adjustable body connected to the rockers and adjustable independently thereof, substantially as described, and for the purpose set forth.

3. A chair having removable rockers and a body connected to the rockers by means of vertical perforated posts and pins, substantially as shown and described, for the purpose set forth.

4. A chair having a base, rockers supported on the base, body connected to the rockers by perforated posts and pins, and a hook on the base to engage one of the pins on the rockers, for the purpose set forth.

JULIA LUEDERS.

In presence of—

GEO. H. KNIGHT,

EDW. S. KNIGHT.
